DESIGN FOR AN ELECTRIC SWITCH UNIT

Daniel E. Reed, Norwalk, Conn., assignor to Yankee Metal Products Corp., Norwalk, Conn., a corporation of New York

Application August 5, 1938, Serial No. 79,124

Term of patent 14 years

To all whom it may concern:

Be it known that I, Daniel E. Reed, a citizen of the United States, residing at Norwalk, county of Fairfield, and State of Connecticut, have invented a new, original, and ornamental Design for Electric Switch Units, of which the following is a specification, reference being had to the accompanying drawing, forming a part thereof, and in which—

Figure 1 is a top plan view of an electric switch unit, showing my new design.

Figure 2 is a side elevational view of an electric switch unit, showing my new design.

The dominant features of my design are illustrated in solid black lines in the drawing.

I claim:

The ornamental design for an electric switch unit, as shown and described.

DANIEL E. REED.
